UNITED STATES PATENT OFFICE.

CLARK E. BILLINGS, OF MIDDLESEX, VERMONT.

REVERSIBLE LATCH.

SPECIFICATION forming part of Letters Patent No. 286,580, dated October 16, 1883.

Application filed February 23, 1883. (Model.)

To all whom it may concern:

Be it known that I, CLARK E. BILLINGS, a citizen of the United States of America, residing at Middlesex, in the county of Washington and State of Vermont, have invented certain new and useful Improvements in Door-Latches, of which the following is a specification, reference being had therein to the accompanying drawings.

10 My invention relates to door-latches; and it consists of the construction and combination of the latching and locking devices, as hereinafter set forth.

15 In the drawings, Figure 1 is a plan view without the removable plate, showing the construction and positions of the devices when the latch-bolt is thrown out and locked. Fig. 2 is the same view, showing the bolt thrown back. Figs. 3, 4, and 5 are views of the external devices for operating the latch-lock attached to a door. Fig. 6 shows in perspective the external locking devices detached used with my spring-latch. Fig. 7 shows in perspective the external locking devices detached used 25 with my gravitating latch. Fig. 8 is a view of the bent key. Fig. 9 shows the locking device applied to the gravitating latch.

A is the latch-bolt, provided with the double recesses b b and the double flanges b' b' on its 30 end, formed to catch the lug c on the screw-stud c', forming the stop to the outward throw of the latch-bolt.

B is a tumbler, pivoted on the pin d. This 35 tumbler is provided with the flanged end d' and the lugs c² c³ on opposite sides of the tumbler, forming the bearings of the lugs d² d³ on the knob-lever C.

D is a spring, the forward end of which extends into a recess in the lower part of the lug 40 c² and bearing against a rounded projection or lug, c⁴, on the tumbler, and the other end of the spring is inserted between and held by the studs h h', formed on the latch-case. By this construction and adjustment of the tumbler 45 near the front part of the latch-bolt and the location of knob-shank near the back part of the latch-case, and the arrangement of the spring, increased power is obtained to overcome the friction of the bolt-knob and con-

nnecting devices, and thus secure with certainty 50 the outward throw of the latch-bolt, while it places the knob at the greatest possible distance from the door-jamb.

E is a detent-stud formed on the sleeve f, having through it a square socket to receive 55 the square shank or spindle f', attached to the circular plate f², provided with a pin or knob, f³. This plate is let in flush with the face of the door, and the knob-rose k extends partly over it, and a hook, k', is pivoted on a screw 60 in the door, in position to hook over the pin f³, as shown in Fig. 3 of the drawings. The shank f' extends through the door and sleeve f into the inner end of the socket f⁴, formed on the knob-rose f⁵, in position to receive the end of 65 the key F, bent as shown, to enable the key to be readily inserted.

The locking device is readily applied to my 70 gravitating latch patented August 17, 1880, No. 231,260, as illustrated in Figs. 7 and 9, in which case a straight key may be used; and instead of attaching the shank f' to the circular plate, the shank is attached to an annular head, a, provided with a small knob, a', and a notch, a², and a recess, forming a shoulder to 75 receive the flange a³ of the rose H, constructed to receive and hold in place the head adjusted to turn freely in the rose, which is provided with a notch, a⁴, corresponding in size with the notch a², to receive the locking-hook k', 80 pivoted on one of the screws which fasten the rose to the door.

The external devices for operating the latch-locking devices are placed on the inner face of 85 the door for the purpose of locking the latch from the inside of the room. The shank f' must be inserted through the sleeve f in such position as will place the pin f³ or the notch a² in position to receive the hook k' when the detent E is turned against the end of the latch-bolt A, as shown in Fig. 1 of the drawings.

The latch-case may be made to receive the 90 devices of an ordinary door-lock, as shown in dotted lines in Fig. 1 of the drawings.

I am aware that various devices have been 95 used for locking door-latches, and my present invention, relating to the latches and their locking devices, consists in and covers only

the particular construction, arrangement, and combination of the devices herein specifically set forth and claimed.

What I claim as new, and desire to secure by Letters Patent, is—

1. The combination of the latch-bolt A, having the double recesses b b near its front end and the double flanges b' b' on its rear end, the screw-stud c', provided with the stop-lug c, the tumbler B, pivoted at its lower part, near the front of the latch-case, and provided with the flanged end d', extended into one of the recesses of the bolt, and having the lugs c² c³ on opposite sides of the tumbler, the knob-lever C, arranged on a spindle located near the rear of the latch-case, and provided with the lugs d² d³ on the forward part of the lever, in position to engage the lugs on the tumbler, and the spring D, secured in place by the studs h 15 and h', and having its forward end arranged in a

cess in the lug c³ of the tumbler, said tumbler being provided with a curved bearing for the spring, substantially as and for the purposes described.

2. The combination, with the detent E, formed 25 on the sleeve f, having through it an angular socket, of the angular shank or spindle f', provided at one end with the circular plate f², adapted to be let in flush with the inner face of the door, and provided with a pin, f³, located 30 in position to receive and lock against the pivoted hook h', substantially as and for the purposes described.

In testimony whereof I affix my signature in presence of two witnesses.

CLARK E. BILLINGS.
